UNITED STATES PATENT OFFICE.

SAMUEL BUCHSBAUM, OF CHICAGO, ILLINOIS.

FULL-SOCKET.

1,253,141.

Specification of Letters Patent.

Patented Jan. 8, 1918.

Application filed July 26, 1916. Serial No. 111,777.

To all whom it may concern:

Be it known that I, SAMUEL BUCHSBAUM, a citizen of the United States, residing at Chicago, in the county of Cook and State of Illinois, have invented a certain new and useful Improvement in Pull-Sockets, of which the following is a full, clear, concise, and exact description, reference being had to the accompanying drawings, forming a part 10 of this specification.

My invention relates to electric switching devices and has for its object the provision of an improved switch mechanism which is of use in a multitude of devices such for 15 instance as pull sockets or key sockets.

In accordance with my invention I have a rotatable element which when rotating in either direction of rotation is adapted to impart a quick make and a quick break of the 20 circuit controlled by the switch which is under the control of said rotating element.

I will explain herein my invention as more specifically applied to a pull socket movement and also a key socket. These particular 25 forms are set forth more in detail in the accompanying drawing, in which—

Figure 1 shows an elevation of a pull socket;

Fig. 2 shows a partial sectional view along 30 line *a—a* of Fig. 1;

Fig. 3 is a detail view of the ratchet mechanism employed;

Fig. 4 is a perspective view showing certain parts separated more clearly to reveal 35 features of construction;

Fig. 5 is a view similar to Fig. 2 of the device as applied to a key socket, and

Fig. 6 is a fragmentary view illustrating 40 a detail of construction.

In Fig. 1 I show the ordinary form of 45 socket 1 as operated by the pull chain 2. The pull chain is preferably operated through a bell shaped opening 3 as more clearly shown in Fig. 2.

My improved switch mechanism includes 50 a switch element 4 having the contact blades 5, 5 integrally associated with a link 6. The switch element 4 has its link projecting through an abutment 7 against which abutment 55 rests a spring 8 preferably encircling said link 6. The switch element at its free extremity near the blades 5 has a flat section 9 which is adapted to slide along the inner face of a rocker element 10. This rocker element is pivoted upon the studs 11 which

pass through the holes 12, 12 formed in ears 13, 13 projecting integrally from said rocker element 10. These studs 11 project from the projection 11^a, which projection at the same time serves to support the element 18 as 60 shown more clearly in Fig. 6. The extremities of the rocker 10 are bent in opposite directions as more clearly apparent from Fig. 4, thus forming abutments 14, 14, and 15, 15 which serve as stops for the element 65 4. The oppositely turned lugs or ears 16, 16 are designed to be engaged by the rotatable operating element which controls the device, as will be presently explained.

It will be readily apparent that if the 70 rocker element is tilted from the position it occupies in Fig. 2 so that it moves clockwise until the link 6 is moved beyond the line joining the center line of the spindle 11 and the center line of the hole through which 75 said link projects in the abutment 7 that then the spring 8 will force this switch element into its opposite position through a contra-clockwise movement wherein element 4 then abuts against the abutments 14 instead of the abutments 15 as illustrated in Fig. 2. A reverse movement of the rocker 10 will of course restore the switch element 4 by snap action into the position of Fig. 2. In order to move the rocker from the position shown in Fig. 2 by a clockwise rotation 80 into a position at or near its limiting position to the other side, such for instance as shown in the position of Fig. 5, I utilize a 85 rotating element consisting in this instance 90 of a shaft 17 having at its right hand extremity an angularly displaced section 18. The element 17, 18 is made of a piece of material rounded in cross-section, thus to facilitate its manufacture, said element being 95 merely bent into the form shown. The diagonal section 18 is partly rounded at its extremities to provide a more gradual movement as will presently appear. The rotatable element 17, when occupying the position of Fig. 2, holds the rocker 10 in the position shown. If now, this diagonal section 18 is moved about into its alternative position as shown in Fig. 5, then it of course carries the rocker 10 with it and as soon as 105 the movement has been sufficient to permit the spring 8 to pass the dead center, this spring forces the parts into the position of Fig. 5 by snap action. It of course makes 110 no difference what might be the direction

of rotation of the rotatable element 17 as the movement from one limiting position by either direction of rotation will carry the diagonal strip 18 into its alternative position.

5 In the construction of Fig. 5 this is taken advantage of by supplying the rotatable element 17 with a key 19, thus to form a key socket.

In Fig. 2 the same result is accomplished 10 when the chain 2 is successively pulled, this chain acting upon a rotatable sleeve 20 loosely carried about the rotatable element 17. The rotatable element in this instance has a pin 21 passing therethrough. The 15 sleeve 20 is likewise provided with two spring catches 22 and 23 held down in position at their extremities, as at 25, to engage the stud 21. A spring 26 forces the sleeve 20 to the right (Fig. 2) and at the same 20 time tends to rotate this sleeve in a clockwise direction, referring to Fig. 3, or what might be a contra-clockwise direction if the device of Fig. 2 were looked at in the direction of the arrow *b*. A suitable stop 27 25 limits this reverse or retractile movement of the sleeve 20.

It will thus be seen that I have provided a switch structure by which a quick make and a quick break may be obtained by controlling the switch element in a suitable 30 manner from a rotatable element. The arrangement is such moreover that the parts for the key socket and pull socket are practically interchangeable by merely substituting the control mechanism of one for the 35 control mechanism of the other, the actual switch structure and its parts remaining the same.

It is thought that the true nature of my 40 invention will thus be readily apparent to those skilled in the art.

Having however thus described one form which my invention may take, what I claim

as new and desire to secure by Letters Patent is:

1. A switch movement of the character described comprising a switch element, and means for moving said switch element by snap action from either limiting position to the other, said means including an oscillatingly mounted rocker, a rotatable control element coöperating with said rocker to move said rocker alternately from one limiting position toward its other limiting position, said switch element being slidable 55 along said rocker, a spring for engaging said switch element and adapted to force it into either limiting position at the opposite extremities of said rocker, and a stem integral with said switch element inclosed by the 60 convolutions of said spring.

2. A switch movement of the character described comprising a switch element, and means for moving said switch element by snap action from either limiting position to the other, said means including an oscillatingly mounted rocker, a rotatable control element coöperating with said rocker to move said rocker alternately from one limiting position toward its other limiting position, said switch element being slidable 70 along said rocker, a spring for engaging said switch element and adapted to force it into either limiting position at the opposite extremities of said rocker, a stem integral 75 with said switch element inclosed by the convolutions of said spring, and an abutment for the free extremity of said spring slidably supporting said stem.

In witness whereof, I hereunto subscribe 80 my name this 25th day of May, A. D. 1916.

SAMUEL BUCHSBAUM.

Witnesses:
